WARD BLACKBURN, OF LOS ANGELES, CALIFORNIA

WELL-FLOWING APPARATUS

Application filed May 13, 1929. Serial No. 362,522.

This invention relates to a means for flowing oil wells by the use of gas or air pressure and by withdrawing successive upper strata of oil from the well until the fluid level in the well has been lowered to a point where the well can be flowed from the bottom of the tubing.

In operating deep oil wells it is at times very difficult to start the flow of oil upwardly through the flow pipe because of the high fluid level in the casing and also, at times because of an excessively high rock pressure. I overcome this difficulty by withdrawing successive upper strata of oil from the casing until the fluid level is lowered to a point where ordinary gas pressures will cause the well to flow.

An object of my invention is to provide a well flowing apparatus which is adapted to be positioned at different levels in the flow tubing and which will automatically direct the flow through the uppermost apparatus and continue to flow through said uppermost apparatus until the fluid level drops below said apparatus.

Another object is to provide a well flowing apparatus of the character stated, the intake ports of which may be either automatically or manually opened and closed.

Still another object is to provide an apparatus of the character stated which is simple in construction, effective in operation, and inexpensive to manufacture.

Other objects, advantages, and features of invention may appear from the accompanying drawing, the subjoined detailed description, and the appended claims.

In the drawing

Figure 1 is a fragmentary side elevation of the tubing with my apparatus shown thereon and with the casing shown in section.

Figure 2 is an enlarged longitudinal sectional view of one of my well flowing apparatuses.

Referring more particularly to the drawing, the numeral 1 indicates the usual casing which is provided in the well and 2 illustrates the usual flow tubing. It is easy to ascertain the level at which the fluid stands in the casing and my flowing apparatuses 3 are spaced

throughout the fluid area so that the fluid level may be reduced by successive stages until the well can be flowed with the usual gas pressure.

My apparatus comprises a body 4 on the upper end of which a threaded coupling 5 is provided into which the tubing screws. A collar 6 screws onto the lower end of the body 4 and is also threaded to receive the tubing. A cylinder 7 surrounds the body 1 and is pressed thereon against the coupling 5. The cylinder 7 is bored out to provide an annular chamber 8 between the body 4 and the cylinder.

A reciprocating sleeve 9 is provided with an upper enlarged flange 10 which fits accurately in the chamber 8. The lower portion of the sleeve 9 is reduced, as shown in Figure 2, and, therefore a shoulder 11 is provided below the flange, the purpose of which will be further described. A plurality of ducts 12 extend through the body 4 into the chamber 8 adjacent the upper end of said chamber.

A plurality of intake ports 13 extend through the body 4 below the lower edge of the cylinder 7 and the sleeve 9 is provided with ports 14 which are adapted to align with the ports when the sleeve is in its lowermost position, as shown in Figure 2. When the sleeve 9 moves upwardly the ports 13 will be closed and no fluid can enter therethrough. A screen ring 15 extends around the ducts 12 to prevent any sand or débris from passing into the chamber 8.

The operation of my apparatus is as follows: Gravity will normally move the sleeve 9 downwardly until the sleeve engages the top of the collar 6 and at this point the ports 13 are open. However, if for some reason the sleeve should stick pressure can be exerted in the tubing and this pressure extending through the ducts 12 will positively force the sleeve downwardly until the ports 13 are open. Pressure is now exerted in the casing 1 upon the top of the fluid and this fluid passes through the ports 13 and upwardly in the tubing until the fluid level passes below the ports.

During this operation of lowering the fluid level it will be evident that the pressure in

the casing must equal the static head of the fluid in the tubing plus the friction of the fluid in the tubing. That is, static head plus friction is equal to the gas pressure in the casing.

Now the moment the fluid passes below the ports 13, we still have the same condition as stated above. The gas continues to push the liquid out of the top of the tubing, thus reducing the foot head load. That is, the liquid weighs for example, .4 pound per square inch, per foot height, and each foot of liquid that is removed reduces the head pressure by that amount per square inch and this liquid is replaced by gas of negligible weight.

Since the ports 13 are relatively small in area compared with the area of the casing and tubing, the gas cannot expand fast enough to maintain the pressure, that is, there cannot be an equalization of pressure in the casing and tubing. Consequently, because of the greater pressure in the casing we have an upward force exerted on the shoulder 11 and on the bottom of the sleeve 9 and the sleeve will be forced upwardly and the ports 13 will be closed.

If for some reason this action above stated does not occur, the sleeve 9 can be manually closed in the following manner: The usual valve at the top of the tubing is closed. Gas pressure is continually forced into the casing and since the tubing is closed, we will arrive at an equal pressure in both the casing and the tubing. The valve on the top of the tubing is now quickly opened and this sudden release of pressure in the tubing cannot be instantly equalized in the apparatus for the reason that the ports 13 are relatively small in area and because of the higher pressure in the casing the sleeve 9 will be closed. When the sleeve has been moved upwardly and the ports 13 are closed, the next lower apparatus comes into use and the well is flowed therethrough until the same action occurs.

Having described my invention, I claim:

1. In an oil well including casing, flow tubing in said casing, a plurality of superposed well flowing apparatuses in said tubing, said apparatuses comprising a body, threaded sections at both ends of said body to which said tubing is secured, a reciprocating sleeve slidably mounted on said body, said body having an annular chamber into which said sleeve extends, said body having a plurality of intake ports therein, said sleeve having ports therethrough adapted to aline with said first named ports when the sleeve is in lowermost position, said sleeve being adapted and arranged to be moved upwardly when there is an unbalanced pressure in the casing and the tubing.

2. In an oil well including a casing, flow tubing in said casing, a plurality of superposed well flowing apparatuses in said tubing, said apparatuses comprising a body,

threaded sections at both ends of said body to which said tubing is secured, a reciprocating sleeve slidably mounted on said body, said body having an annular chamber into which said sleeve extends, said body having a plurality of intake ports therein, said sleeve having ports therethrough adapted to aline with said first named ports when the sleeve is in lowermost position, said sleeve being adapted and arranged to be moved upwardly when there is an unbalanced pressure in the casing and the tubing, and said body having a plurality of ducts therein extending into said chamber adjacent the upper end of said chamber.

3. In an oil well including a casing, flow tubing in said casing, a plurality of superposed well flowing apparatuses in said tubing, said apparatuses comprising a body, threaded sections at both ends of said body to which said tubing is secured, a reciprocating sleeve slidably mounted on said body, said body having an annular chamber into which said sleeve extends, said body having a plurality of intake ports therein, said sleeve having ports therethrough adapted to aline with said first named ports when the sleeve is in lowermost position, said sleeve being adapted and arranged to be moved upwardly when there is an unbalanced pressure in the casing and the tubing, and said body having a plurality of ducts therein extending into said chamber adjacent the upper end of said chamber, and a screen extending over said ducts.

4. In an oil well including a casing, and flow tubing therein of a well flowing apparatus, comprising a body, threaded couplings at both ends of said body to which the tubing is screwed, a cylinder pressed onto said body, said cylinder and body forming an annular chamber therebetween, a sleeve slidably mounted on the body and in said annular chamber, a flange at the upper end of said sleeve adapted to closely fit in said chamber, a plurality of intake ports in said body below said chamber, said sleeve having a plurality of ports therethrough adapted to register with said first named ports when the sleeve is in the lowered position, said sleeve being adapted to move upwardly and close said ports when there is an unbalanced pressure between the outside and the inside of the tubing.

5. In an oil well including a casing, and flow tubing therein, of a well flowing apparatus, comprising a body, threaded couplings at both ends of said body to which the tubing is screwed, a cylinder pressed onto said body, said cylinder and body forming an annular chamber therebetween, a sleeve slidably mounted on the body and in said annular chamber, a flange at the upper end of said sleeve adapted to closely fit in said chamber, a plurality of intake ports in said body be-

low said chamber, said sleeve having a plurality of ports therethrough adapted to register with said first named ports when the sleeve is in the lowered position, said sleeve being adapted to move upwardly and close said ports when there is an unbalanced pressure between the outside and the inside of the tubing, and a plurality of ducts extending through said body into said chamber adjacent the upper end of the chamber.

10 In testimony whereof, I affix my signature.
JESSE E. B. DANIEL.
